VALVE GRINDING TOOL

Lawrence O. Beard, Lancaster, Pa.

Application May 11, 1934, Serial No. 725,170

7 Claims. (Cl. 51—187)

My invention relates to a tool for grinding valve seats and more particularly the conical seats formed in the motor blocks of internal combustion engines.

5 The principal object of the invention is to provide a tool having a flexible paper or cloth abrasive element which is mounted for ready removal and which may be easily renewed when worn.

10 Another object of the invention is to provide a tool adaptable for use with soft as well as hard surfaces.

Another object is to provide a tool that can be handled with either a bit brace, a breast drill, or quarter inch electric drill.

15 These and other objects will be apparent from the following description in which the same numerals designate similar parts in the several views.

In the drawing:

20 Figure 1 is a side elevation of the assembled tool in operative position, the pilot stem not being shown;

Figure 2 is a side elevation of the shank and pilot stem;

25 Figure 3 is a side elevation of the grinding head;

Figure 4 is a plan view of the grinding head;

Figure 5 is an elevation of the clamping member for securing the abrasive member to the grinding head;

30 Figure 6 is a plan view of the clamping member;

Figure 7 is a plan view of the clamp nut;

Figure 8 is a plan view of the abrasive disk; and

Figure 9 is a plan view of the washer.

35 Referring more specifically to the drawing, the numeral 1 designates the tool generally comprising a shank 2 of standard size having a portion 3 of suitable length reduced in diameter and threaded at its lower end, as at 4, and having 40 its lower end bored to receive a pilot stem 5, and 6 is a conically shaped grinding head having a cylindrical bore 7, adapted to loosely receive the shank 2, when the parts are assembled in a manner hereinafter described. The grinding head has 45 a flat top surface 8 and a conical working surface 9 of suitable pitch or slope and having a substantially narrow flat bottom surface 10. Relatively deep substantially V shaped grooves 11, preferably five in number, are cut radially into the

50 grinding head on a slightly decreased pitch from that of the cone working surface 9, the grooves extending from the top surface 8 to the flat bottom surface 10. A washer 12 is adapted to slip over the threaded end 4, and a centrally bored 55 clamp nut 13, when screwed home on the threads

4, tightly clamps the washer against the flat surface 10, of the grinding head.

A thin circular disk of emery cloth or paper 14, having an aperture 15 constitutes the abrasive element for grinding the valve seat, not shown.

5 The abrasive disk 14 is sleeved over the conical working surface 9 of the grinding head and caused to conform closely to the contour of the latter by means of a substantially rigid or semi-

rigid clamping member or spider 16 formed of 10 slightly yielding metal. Clamping member 16

comprises a narrow annular or ring like portion 17 the bore and diameter of which are respectively just sufficient to permit of the clamping member

being sleeved over the reduced portion of the shank and in abutting relation with washer 12.

Projecting upwardly and outwardly from the annulus 17 of clamping member 16, are a plurality of arms 18, one for each groove 11, in which

grooves these arms are adapted to snugly fit when 20 the latter, together with the adjacent portions

of the abrasive disk, are pressed thereinto. The arms are V shaped and tapered to snugly fit into

and conform with the grooves 11, and serve to 25 clamp or press the abrasive cloth against the sides of the grooves, the upper inner end edges

of the arms being slightly rounded or concave as at 18a to eliminate sharp cutting edges and allow

some slight stretching movement of the cloth

thus preventing the cloth from cracking or tear-

ing when forced home in the grooves 11. The 30 clamp bottom or annulus 17 is slightly concave as at 17a to press the abrasive cloth against the base of the grinding head and allow some slight

stretching of the cloth at this point. Those 35 portions of the disk 14 which are pressed by arms 18 into the grooves 11, have their outer peripheral edges squared off, as at 19, so that the margins

of the disk within the groove will not extend over

the margin of the groove and thus become frayed

40 by the arms. The size of these squared off areas is so proportioned with respect to the working surfaces or areas of the cutter head, extending

between the grooves 11, as to insure a smooth close

45 fit between the parts.

It will be understood from the foregoing that 50 the washer 12 engages the annulus of the clamping member 16 and the clamp nut 13 threadedly engages threads 4 and tightly clamps the grinding head and abrasive disk 14 together. The end of the shank 2 is squared as at 20, to facilitate use of a wrench in grinding the valve seat, or a rod may be inserted in a circular hole 21, located

55 below the squared end, and by means of which the tool may be rotated.

To assemble my device I slip the grinding head with the abrasive disk 14 and clamping member 16 fitted thereon onto the reduced portion 3 of the shank, and slide the washer 12 thereon and then screw home the clamp nut 13 on threads 4 of the shank, thus tightly clamping the abrasive element and the grinding head together. The pilot stem 5 may be screwed into the end of shank 2 either before or after the washer 12 and nut 13 have been applied. After inserting the head into the valve seat, the tool is rotated by means of either a wrench or rod, as previously described.

To replace a worn or damaged abrasive disk 14, it is merely necessary to remove the clamp nut and washer, slip the clamping member 16 off the shank, and remove the disk. A fresh disk can then be easily and expeditiously mounted upon the grinding head.

Having thus described my invention, what I claim is:

1. A tool for grinding valve seats comprising a shank, having a conical grinding head thereon, adapted to engage the valve seat, said head having V shaped recesses formed therein, an abrasive member adapted to partly cover said head and fit in said recesses, a clamping element for clamping said disk against said grinding head having V-shaped arms adapted to fit into the grooves formed in the head for holding the disk against said head.

2. A tool for grinding valve seats comprising a shank with a reduced portion thereon, having a conical grinding head thereon, said head having radial V shaped recesses formed therein, an abrasive member adapted to fit over said head, a substantially rigid clamping element having V shaped arms for clamping said abrasive member in said recesses and against said head.

3. A tool for grinding valve seats comprising a shank having a reduced portion, a conical grinding head mounted on said reduced portion, said head having five V shaped radial tapered grooves therein, a flexible abrasive member substantially covering said head, a substantially rigid clamping element having V shaped tapered arms for

clamping said abrasive member against said head, and means on said shank for holding said clamping member in position against said head.

4. A tool for grinding valve seats comprising a shank having a reduced threaded portion, a conical grinding head mounted on said reduced portion, said head having five V shaped radial tapered grooves formed therein, a flexible abrasive member substantially covering said head, a semi-rigid metal clamping element having V shaped tapered arms for clamping said abrasive member against said head, threaded means threaded on said reduced portion for retaining said clamping member in position against said head.

5. A tool for grinding valve seats comprising a shank, a conical grinding head mounted thereon, relatively deep, radial V shaped grooves formed therein, an abrasive disk removably mounted on said head, a metal clamping member having V shaped tapered arms adapted to fit in the grooves formed in the shell for holding the abrasive disk against said head, said clamping member having means thereon for allowing the abrasive material to stretch when clamped, a clamp nut and washer mounted on said shank for retaining the clamping member and abrasive disk in position against said head.

6. A tool for grinding valve seats comprising a shank, a conical grinding head mounted thereon having V shaped grooves formed therein, an abrasive disk substantially covering said head, a semi-rigid metal clamping member having V shaped tapered arms adapted to fit in said grooves for clamping the abrasive disk against the sides of said grooves, concaved surfaces on said clamping element to permit said abrasive disk to stretch.

7. A tool of the character described having a grooved grinding head, an abrasive element substantially covering said head, a semi-rigid metal clamping member having V shaped tapered arms, the upper ends thereof and the bottom of said element being concave to permit stretching of said abrasive element.
